UNITED STATES PATENT OFFICE

JOHN J. BAUSCH, OF ROCHESTER, NEW YORK, ASSIGNOR TO BAUSCH AND LOMB
OPTICAL COMPANY, OF ROCHESTER, NEW YORK, A CORPORATION OF NEW YORK

LENS GRINDING AND POLISHING MACHINE

Application filed August 6, 1921. Serial No. 480,220.

This invention has to do with apparatus for grinding and polishing lenses, one object being to provide a machine of this variety with efficient tool supporting means of a conveniently adjustable character for disposing the tool in a wide range of positions relative to the lens holder.

Another object is to provide tool supporting means constructed and adapted to facilitate the use of a plurality of tools, either one at a time, or simultaneously, as for example, in the manufacture of bifocal lenses, together with means for retaining one or more of the tools in a position spaced from the lens holder when not in use or for facilitating inspection or replacement of the tools or work. Another object is to provide convenient and effective driving means for the tool accommodating adjustments of the above character.

To these and other ends the invention consists in certain improvements and combinations of parts, all as will be hereinafter more fully described, the novel features being pointed out in the claims at the end of the specification.

In the drawings:

Figure 1 is a front elevation of a machine embodying the present invention.

Figure 2 is a top plan view of the same.

Figure 3 is a side elevation.

Figure 4 is an enlarged detail sectional view on the line 4^a—4^a of Figure 2.

Figure 5 is a similar sectional view on the line 5^a—5^a of Figure 4.

Figure 6 is a similar sectional view on the line 6^a—6^a of Figure 2 showing the parts in a different position.

Figure 7 is a similar sectional view on the line 7^a—7^a of Figure 2, and

Figure 8 is a sectional view on the line 8^a—8^a of Figure 7.

Similar reference numerals throughout the several views indicate the same parts.

The embodiment of the invention at present preferred and disclosed herein by way of illustration comprises a main frame indicated generally at 10, Figure 1, having an upwardly, hollow, column portion 11 in which is journaled in any suitable manner a vertical spindle 12 on the upper end 13 of which is

detachably fitted a lens holder 14 to which is cemented a lens 15, this construction and arrangement being well understood in the art and requiring no detailed description. The lens holder spindle has preferably fixed thereon adjacent its lower end a grooved pulley 16 and the frame is cut away on opposite sides as at 17 for the application of a driving belt to the lens holder spindle from either side of the machine. The frame is shown as mounted on a bench or table 18.

The frame is provided with means for adjustably supporting a pair of tool spindles either of which may be brought from an inoperative position into cooperation with the lens holder so that the tools may be employed individually or may be used simultaneously as is desirable in the grinding of bifocal lenses. To this end column 11 of the frame

has fixed thereon and projecting laterally therefrom at opposite sides brackets 19 and 20 having adjustably mounted thereon movably connected parts which support the tool spindles for adjustment to different operating positions relative to the lens holder, and

as the parts for supporting each tool are substantially the same a description of the supporting means for one tool will apply to both. Bracket 19 has its outer end formed in the shape of an open frame in the opposite sides of which are supported the ends of a shaft 21 on which is pivotally supported an upwardly extending lever 22 the lower end of which is connected by means of one or more springs 23

with a fixed portion of the bracket, so that the upper end of the lever is normally urged in an outward direction away from the lens holder. A stop or set screw 24 is threaded into a lug 25 on the end of the bracket

and is provided with an operating head 26 by rotation of which the inner end of the set screw may be moved toward or from the lens holder in contact with lever 22 for adjusting the position of the latter, the lever of course being held in contact with the stop or set screw by spring 23. A lock nut 27 may be provided on the screw to hold it securely in adjusted position.

The upper end of lever 22 is formed with spaced arms 28 in which are journaled the

ends of a shaft 29 having fixed thereon, Figure 2, a sleeve 30 carrying spaced arms 31. The outer ends of these arms have fixed there-in the ends of the shaft 32 on which is pivot-ally supported a part, or lever 33, in a bearing 34 at the inner end of which the tube spindle is rotatably supported. The spindle is shown at 35, Figure 4, as extending below lever 33 and provided at its lower end with a substantially spherical portion 36 loosely engaging a recess in the tool 37. The portion 36 is flattened on one or more sides and the recess with which it engages in the tool correspondingly shaped so that rotation of the spindle positively rotates the tool, while the latter, however, is loosely connected with the spindle so that its grinding or polishing surface may conform at all times to the surface of the work. The tool shown in the present instance is of the ring type having a peripheral grinding or polishing annulus 38 and a recessed interior portion 39, as well understood in the art.

Lever 33 has fixed on the under side of its inner end a block 40; the lever and block being recessed to form a housing in which is a spiral gear 41 fixed on the tool spindle and meshing with a corresponding gear 42 fixed on a shaft 43 journaled in the lever and rotated by suitable driving means hereinafter described for driving the tool spindle.

The lens shown in the present instance is of the bifocal type having an outer distance portion 44 and a central reading portion 45, the tool 37 being arranged in the present instance for grinding or polishing the reading portion. At 46 is shown a second tool operating simultaneously upon the distance portion of the lens and supported and driven by means similar to that described for the tool 37. Means are provided as later described for the operation of either one of the tools alone or both simultaneously as is frequently desirable in the manufacture of lenses of this type although of course the machine is adapted for producing various other types of lenses.

While the flexible connection described between the tool spindle and tool permits the latter to conform to the surface operated upon regardless of the exact angle of the axis of the spindle, it is preferred to support the latter so that it may be adjusted to bring its axis coincident with the rotary axis of the tool. To this end there is provided a spring 47, Figure 1, connected at one end to a finger 48 fixed on the outer end or tail of lever 33, the other end of the spring being attached to a web 49 integrally connecting the arms 31. This end of lever 33 also carries a stop or set screw 50 in position for engagement of its end with the web portion 49 of the arms 31. Spring 47 holds the set screw of the lever in contact with the arm so that by adjustment of the set screw the lever may be adjusted on

its pivot and a corresponding angular adjustment of the axis of the tool spindle obtained. It is apparent from this construction that by the adjustment of set screw 50 to effect relative adjustment between the axes of rotation of the spindle and lens holder and also the adjustment of set screw 24 for moving the tool spindle substantially transversely of the axis of the lens holder, the spindle may be given any desired position relative to the latter, including, for example, the arrangement of the tool spindle with its axis passing through the center of curvature of a lens surface under treatment.

When it is desired to render one of the tools inoperative or to inspect or remove the tools or work, the arms 31 may be swung about shaft 29 as a pivot to the position shown in Figure 6. For holding a tool spindle in such out-of-the-way position spaced from the tool holder there is provided on lever 22 a leaf spring 51 with which engages a beveled lug 52 fixed on sleeve 30 of the arms 31. When the latter are moved upwardly to the position described these parts form a yieldable detent securely holding the tool spindle in such a position but admitting of its convenient return to operating position by the exertion of sufficient pressure on the arms 31 to force the lug 52 out of contact with spring 51. As shown in Figure 6 sleeve 30 is so shaped as to engage, in this spaced position of the tool spindle, with a portion of lever 22, thereby limiting the outward movement of the spindle supporting arms.

For holding the tools against the work with the pressure desired to accomplish the grinding or polishing operation, there is fixed to the web portion 49 of the arms 31 a cord or other flexible connection 53 extending downwardly below the support or table 18 and carrying at its lower end a weight 54. This gravity means for pressing the tool toward its work is thus so disposed as to be out of the way but is nevertheless constantly connected with its tool by means accommodating the adjusting movement of the latter and also its movement to the spaced position described.

The present invention embodies also an advantageous driving means for the tool spindles comprising for each spindle a rotary driving element such, for example, as a pulley, in relatively fixed location on the frame and connected by flexible and detachable means with the tool spindle so that the adjusting movements of the latter are not interfered with and the spindle may be conveniently disconnected from its driving means and moved to the spaced position described. This means comprises preferably a sleeve 55, Figures 2 and 5, fixed on the end of the shaft 43 and having in its opposite sides longitudinal recesses or slots 56 extending inwardly from the end of the sleeve and termi-

nating in enlarged recesses 57. The bore of the sleeve receives a ball like end 58 of a rod or shaft 59 of less diameter than the sleeve bore, and end 58 of the shaft is provided with 5 transversely extending pins 60 which are received in the slots 56 and recesses 57. This construction provides a simple form of universal joint between the driving rod or shaft 59 and the tool spindle, it being apparent 10 that during rotation of shaft 59 the pins 60 thereof engage and rotate sleeve 55, being in engaged relation by the shoulders of recess 57. When the parts are stationary, however, pins 60 may be brought to registry with slots 15 56 in the sleeve and shaft 59 withdrawn from the sleeve, thus detaching the driving connection from the spindle. Shaft 59 at its opposite end is provided with a similar spherical end 61 received in the end of a sleeve 62 fixed in a 20 sleeve 63 rotatably carried in a bearing 64 on an arm 65 extending upwardly from the frame. Sleeve 62 has extending inwardly thereof from its end opposite longitudinal recesses or slots 66 in which are engaged the 25 ends of transverse pins 67 carried by shaft 59, the pins being prevented from removal from the slots by a flange 68 on a collar 69 fixed on sleeve 63. A washer 70 is interposed between collar 69 and bearing 64, and the other 30 end of sleeve 63 has fixed thereon a driving pulley 71 with which a driving belt for the tool spindle may be engaged. Driving shaft 59 is thus also connected with the rotary element or pulley 71 on the frame by means of 35 a universal joint permitting the adjustment of the tool spindle as already described. As shown in the drawings similar driving means are provided for the other tool spindles.

In operation, with the tool spindles in the 40 spaced or out-of-the-way position described, the lens to be ground is attached to its holder and mounted on the upper end of spindle 12. One or more of the tool spindles is then moved to position above the lens and provided with the proper tools. By adjusting set screws 24 and 50 the tool is moved to the desired operating position on the lens and the tool spindle adjusted to the proper angle relative to the axis of the lens holder. The 45 driving means for the tool spindles are then connected with the latter by placing the free end of each shaft 59 in its sleeve 55 and the belts for driving the lens holder and spindles then put in motion to effect the grinding or 50 polishing of the lens. The tools may be conveniently adjusted by means described during the operation of the machine and when it is desired to inspect the work or the tool or to remove either, pulleys 71 are stopped and shafts 59 disconnected from the tool spindles after which the latter may be swung upwardly and away from the lens holder to the position indicated in Figure 6. The machine is thus provided with convenient means 55 for adjusting the tools through the desired

range of operating positions and for moving the same to and from inoperative position spaced from the work. The tool supporting means is constructed and adapted to facilitate the simultaneous use of a plurality of tools or for employing a single tool, as occasion may require. The lens holder and tool spindles are separately driven as is desirable for effecting variation in their relative speeds and the tool spindles are driven by a simple 70 and effective device conveniently disposed at the back of the machine and so constructed as to accommodate the adjustment of the spindle. When the latter is not in use it may be readily disconnected from its driving means, the latter having a stationary position on the frame so that adjustment of the belting from a source of power is unnecessary. While the present machine is intended primarily for fine grinding, polishing, and finishing, it is obvious that other work may be accomplished by properly attaching corresponding tools to the spindles and that various other changes may be made in the details of the construction and operation of the machine within the scope of the appended claims.

I claim as my invention:

1. In a lens grinding machine, the combination with a frame and a rotary lens holder thereon, of a part movably supported on the frame, a tool spindle and a driving shaft for the latter rotatably carried by said part, a driving connection between said spindle and shaft, a pulley rotatably carried on the frame, the movement of said part on the frame permitting adjustment of said spindle to different operating positions relative to said lens holder and also to and from an out-of-the-way position spaced a substantial distance from the lens holder movement to and from said out-of-the-way position being in the direction of a plane substantially transverse to the axis of said pulley and of said driving shaft, and a rod connected at its respective ends with said pulley and shaft by universal joints one of which is detachable to permit movement of the tool spindle to said out-of-the-way position.

2. In a lens grinding machine the combination of an upright frame member, a revolvable lens spindle mounted thereon, an arm extending laterally from the frame member, an upstanding member adjustably pivoted on the outer end of said arm, a horizontally disposed member pivoted upon said upstanding member above said arm, a lever pivoted intermediate its ends upon said horizontally disposed member, adjusting means for said lever spaced outwardly from the pivotal axis thereof, a tool spindle journaled upon the inner end of said lever, a shaft journaled in said lever and operatively connected with the tool spindle intermediate its ends and driving means for said shaft.

3. In a lens grinding machine the combination of a frame, a revoluble lens spindle mounted therein, a support pivotally connected with the frame, a horizontally disposed lever pivoted intermediate its ends upon the support, means adjustably connecting the outer end of the lever with an intermediate portion of the support, a tool spindle journalled in the other end of the lever, a shaft journalled upon the lever and operatively connected with the tool spindle, means whereby the support is mounted for adjustment toward and from the axis of the lens holder, and means for driving said shaft and said lens spindle.

4. In a lens grinding machine the combination of a frame, a revoluble lens spindle mounted thereon, an arm pivotally connected with the frame, a lever pivoted intermediate its ends upon said arm and having its outer end terminating intermediate the ends of the arm, means yieldably connecting the outer end of the lever with the arm, means for adjusting the lever upon the arm, a tool spindle journalled upon the inner end of the lever, a shaft journalled upon the inner end of the lever and operatively connected with the spindle, and means for driving said shaft and said lens spindle.

5. In a lens grinding machine, the combination of a frame and a rotary lens holding member thereon, a support on the frame, a vertically disposed member adjustable upon the support for movement toward the lens holding member, a pair of inner and outer substantially horizontal members, said inner member being pivoted intermediate its ends on the outer member and the latter being pivoted upon the vertically disposed member, means adjustably connecting the inner and outer members intermediate the ends of the latter, yieldable means for holding said horizontally disposed members in adjusted position, a tool spindle journalled on the inner end of said inner member and means for driving said spindle.

6. In a lens grinding machine, the combination of a frame and a rotary lens holding member thereon, a support on the frame, a vertically disposed member adjustable upon the support for movement toward the lens holding member, a pair of inner and outer substantially horizontal members, said inner member being pivoted intermediate its ends upon the outer member and the latter being pivoted upon the vertically disposed member, an adjusting screw threaded in one of said horizontal members and engaging the other to effect relative movement between the same, means yieldably holding said members in adjusted position and means for driving said spindle.

7. In a lens grinding machine, the combination of a frame and a rotary lens holding member thereon, a support on the frame, an

upstanding member adjustable upon the support toward and from the lens holding member, a pair of inner and outer substantially horizontal members, said inner member being pivoted intermediate its ends upon the outer member and the latter being pivoted upon the upstanding member, means connecting the outer end of the inner member with an intermediate portion of the outer member arranged to permit adjustment of said members during operation of the machine, a tool spindle journalled upon the inner member and adapted to overlie the lens holder, a shaft journalled in the inner member and adapted to drive the spindle and means for exerting downward pressure on said inner and outer members during operation of the spindle.

8. In a lens grinding machine, the combination of a frame and a rotary lens holder thereon, a member pivotally connected with the frame and adjustable for bodily movement transversely of the axis of the lens holder, a second member pivoted to swing upon the first, means spaced from the pivotal axis of the second member for adjusting it upon said first member, a tool spindle journalled in spaced bearings upon said second member, a gear on said spindle between said bearings, a shaft journalled in spaced bearings upon said second member and having a gear between said bearings meshing with the first mentioned gear and a flexible drive connection detachably engaging said shaft.

9. In a lens grinding machine, the combination of a frame, a rotary lens holder thereon, a support on the frame, an upstanding member adjustable upon the support toward and from the lens holder and having spaced bearings thereon, a substantially horizontal arm having its outer end pivoted upon said bearings and provided with spaced bearings at its inner end, a lever pivotally supported intermediate its ends by the last mentioned bearings, a tool spindle journalled in the inner end of the lever, means adjustably connecting the outer end of the lever with the arm and means for driving the tool spindle.

JOHN J. BAUSCH.
